UNITED STATES PATENT OFFICE.

EARNEST W. LADD, OF NEW YORK, N. Y.

ANTIRATTLER FOR WINDOWS.

1,406,264.

Specification of Letters Patent. Patented Feb. 14, 1922.

Application filed June 19, 1919. Serial No. 305,407.

To all whom it may concern:

Be it known that I, EARNEST W. LADD, a citizen of the United States, residing in the borough of Manhattan, in the city, county, 5 and State of New York, have invented certain new and useful Improvements in Anti-rattlers for Windows, of which the following is a specification, reference being had to the drawings which accompany and form a part 10 of the same.

The object of my invention is to provide a device to resist or overcome the rattling of window sash in their frames, which device will be efficient in operation and at the 15 same time produced at very low cost. Furthermore, its application to use may be manually made without tool or implement of any kind by inexperienced persons without the necessity of removing the sash from the 20 frame or dismantling the window structure in any manner. Furthermore, the device is made with a self contained securing element to hold the same in place between the sash and the frame, said securing element automatically fastening the device in position 25 and holding it there. Furthermore, the use of my device does not mar or detract in any way from the finished appearance of the sash or frame.

30 In the drawings,

Fig. 1 is a perspective view of a segment of window structure, including my device;

Fig. 2 is an inside elevation view of a window structure also including my device;

35 Fig. 3 is a perspective view of my anti-rattler.

Referring now in detail to the drawings in which similar reference characters refer to similar parts throughout, 1 represents a 40 window frame, 2 a sash, 3 a light inserted in the sash and 4—4 retaining strips all of common construction.

45 5 is my anti-rattling device made of strip metal preferably bow shaped in its general outline and having resilient qualities. 6 represents securing elements in the form of prongs which are preferably turned from the general contour of the strip, the purpose

of these prongs being to secure the said device in position as more fully hereinafter 50 described. Opposite these securing elements, I have provided sliding means 7. The entire structure of my anti-rattler is preferably made in a unitary form as shown.

In order to use my device, the same is slid 55 by hand between the sash and retaining strip of a window. In Figs. 1 and 2, my anti-rattler is shown in position with the prongs 6 embedded in the sash. It is obvious, of course, that the anti-rattler may be inserted 60 in reverse position to that shown so that the prongs 6 would in that case become embedded in the retaining strip of the window structure.

After the device is slid into place as described, the pressure brought upon the same by reason of its position between the sash and retaining strip forces the prongs 6 into the surface intended and effectually secures the anti-rattler against movement on the 70 surface to which it is secured.

It is obvious that many modifications may be made in the device illustrated and described without departing from the principle of my invention, such as changing the form 75 of the ends of the anti-rattler, adopting a different shape for the body of the same, changing the form of the attaching or sliding means, or the shape or position of the prongs, or securing elements. I do not therefore, wish to confine myself to the exact form herein shown and described, but what I desire to cover by Letters Patent is set forth in the appended claim.

Claim:

An anti-rattler for windows adapted to be inserted and concealed between the meeting sides of a sash stile and casing of a window frame and comprising a curved metal spring strip provided with sharp spurs struck up 90 from one of its ends for anchoring said strip to the stile of the sash, its other end being provided with a turned up sliding surface for resilient engagement with the said stile.

EARNEST W. LADD.
